UNITED STATES PATENT OFFICE.

GEORGE S. KYLE, OF CHAMBERSBURG, PENNSYLVANIA, ASSIGNOR OF ONE-THIRD TO JOHN M. McDOWELL, OF SAME PLACE.

DUMPING-WAGON.

SPECIFICATION forming part of Letters Patent No. 453,491, dated June 2, 1891.

Application filed November 10, 1890. Serial No. 370,861. (No model.)

To all whom it may concern:

Be it known that I, GEORGE S. KYLE, a citizen of the United States, residing at Chambersburg, in the county of Franklin and State of Pennsylvania, have invented certain new and useful Improvements in Wagons for Use in Road-Making; and I do hereby declare the following to be a full, clear, and exact description of the invention, such as will enable others skilled in the art to which it appertains to make and use the same.

This invention relates to an improvement in wagons, carts, or vehicles for transporting crushed stone, gravel, earth, or other similar substance or material and delivering the same upon the surface of the ground during the operation of road-making, the object of the invention being to provide simple and efficient locomotive means for distributing crushed stone or gravel evenly over the surface of the road, and thus avoid the laborious operation of shoveling the same several times over in order to properly place it upon the road-surface; and the invention therefore consists, essentially, in the combination, with a wagon having inclines on the bottom thereof, of a dumping leaf or plate arranged, in connection with the bottom opening in the wagon-body, so that at this point the crushed stone or other substance may be automatically delivered through the opening upon the road and caused to fall evenly over the surface of the latter as the wagon travels along, the said leaf or dumping-bottom being opened or closed by means under the control of the driver from his seat; and the invention further consists in certain details in the construction, arrangement, and combination of the several parts, substantially as will be hereinafter described, and then more particularly pointed out in the subjoined clauses of the claim.

In the accompanying drawings, illustrating my invention, Figure 1 is a side elevation of my improved wagon for use in road making or repairing. Fig. 2 is a top plan view of the same. Fig. 3 is a longitudinal section.

Similar letters of reference designate corresponding parts throughout all the different figures of the drawings.

50 A designates the wagon-body, and B the

wheels, said body being provided near its forward end with the driver's seat C.

It is unnecessary to enter here into any detailed description of the construction of the driving-gear of the wagon, as this does not 55 form a part of the present invention. Suffice it to say that the wagon, with its wheels, &c., may be constructed in any suitable and desirable manner. The body may be of any convenient shape and size, the wheels likewise made in any suitable fashion, and the body mounted upon the wheels in such a manner as may be preferred.

My invention is equally applicable for combination with many and various kinds of 65 wagons suitable for hauling stone, gravel, and other similar substances.

The interior of the wagon-body A is provided with inclines running from the ends of the wagon toward the middle point thereof. 70

D denotes the rear incline, and E the forward incline. These inclines form the major portion of the bottom of the wagon. Their relative lengths may vary in different wagons. I am confined and restricted to no 75 particular arrangement or size for this incline surface. Their object will be seen at a glance, as they are intended to support the crushed stone, gravel, or other substance with which the wagon-body is filled, and thus cause 80 the said crushed stone to have a tendency to move toward the point between the two lower ends of the inclines. These inclines do not meet, but their lower ends are separated for a convenient distance, there being located between them a hinged leaf, cover, or dumping-plate F, which is arranged within the opening in the wagon-bottom, said plate F being adapted to cover said opening and thus close and make the entire wagon-bottom intact, 85 and at other times to be opened to a greater or less extent for the purpose of allowing the contents of the wagon to be automatically fed out in an even manner through the outlet thus afforded. This dumping-bottom F is 90 hinged at f f to some suitable part of the wagon-bottom, as shown in Figs. 1 and 3. The size of the opening in the wagon-bottom between the inclines D and E may vary in different wagons. I am restricted to no par- 100

ticular size. Said opening is simply a transverse rectangular opening (although its shape may vary) and the dumping-bottom F is of course of a corresponding shape and size. It 5 becomes necessary to have some means whereby the dumping-bottom F may be operated by the wagon-driver from his seat, so that he may vary the size of the opening in the bottom of the wagon whenever it may be 10 necessary and may close the same or open it when he desires.

One feature of this invention consists in the combination, with the dumping-plate, of means approximate to the driver's seat for 15 controlling the same. As the wagon moves along over the road-surface it is necessary that the driver can have devices within easy reach which he can manipulate for the purpose of controlling the size of the opening in 20 the bottom of the wagon, and, if necessary, closing or opening to the full width. An example of such devices I will now proceed to describe.

a denotes a transverse shaft supported in 25 the sides of the body A and carrying small grooved rollers or pulleys b b, which may be integral with the shaft or movable thereon, as preferred.

Adjoining the driver's seat C, preferably in 30 front thereof, is another transverse horizontal shaft G. This shaft is supported in the sides of the wagon-body A, and projects through each side and carries groove wheel or disks thereon c.

35 e e designate chains, which are firmly connected to the shaft G, or, rather, it may be said, are secured within the grooves of the wheels e c. These chains pass over the grooved wheels or pulleys b b and then pass 40 downward and are connected to the rods d d, the lower ends of which are connected to the dumping plate or door F. Thus it will be seen that as the rods d d draw upward upon the door F the result will be to close the same, 45 and as they relax their upward hold upon the door the latter is allowed to open to a greater or less extent. The connection between the shaft G and the door F may vary, if desired, and, instead of being part chain and part rod, 50 may be entirely chain, or may be ropes or cords or whatever other devices will form or will provide a proper connection between the said shaft G and the door.

I indicate the chains and rods simply by 55 way of example only as one convenient way of operating the door.

On the shaft G near one of the sides of the wagon-body, and preferably within said body, is a gear-wheel H. Alongside of the gear H, 60 and likewise on the shaft G, is a ratchet-wheel I. The ratchet I is engaged by a pawl K, which is pivoted at k to the wagon-body just in front of the driver's seat, said pawl being provided with the spring l, which keeps 65 it in engagement with the teeth of the ratchet. The driver, by pressing his foot upon one end

of the pawl K in the direction shown by the arrow in Fig. 3, may compress the spring and disengage the pawl from the ratchet. This he can do whenever necessity requires. When 70 he releases his foot from the pawl, the spring will again force it into engagement with the ratchet. Above the gear H and meshing therewith is another gear L, carried on a suitable stud and provided with a hand-crank L'. 75 It will thus be seen that by manipulating the crank L' and rotating the gear L the intermeshing gear H will in consequence be rotated, which will impart a rotary motion to the shaft G, and the door F may in this manner be closed. When, therefore, the door F is open and the driver desires to close it, the wagon-body being empty, all that he needs to do is to rotate the crank L' a few times, and this will suffice to effect a closing, and the 80 pawl K will hold the ratchet so that the door F will be held tightly closed. When the driver desires to open the door F, he will simply press his foot upon the pawl K, and then by simultaneously grasping the crank- 85 handle L' allow the weight within the wagon-body to open the door sufficiently far, and then releasing his foot from the pawl allow it to fall into engagement with the ratchet, and thus hold the door at the desired point. 90 In actual practice it will be found that the door when delivering crushed stone upon the road will be open only at a small angle, as shown in Fig. 3. This will insure a steady, uniform, and even delivery of the crushed stone upon the road-surface as the wagon travels along over it. If the wagon is filled with larger stones or pieces of rock, it may be found at certain times advantageous to have the door F open its full width. 95

Having thus described my invention, what I claim as new, and desire to secure by Letters Patent, is—

1. In a wagon for use in road-making, the combination, with the body having interior inclines sloping from the ends toward the middle and an opening in the bottom between the ends of said inclines, of a door for said opening, and devices, substantially as described, consisting of a shaft supported in 110 the sides of the wagon-body above the opening, said shaft having pulleys and connections between the pulleys and said door for regulating the extent to which it may be 115 opened or closed for the purpose of delivering crushed stone or other substances easily upon the road surface. 120

2. In a wagon for use in road-making, the combination, with the wagon-body having interior inclines sloping toward each other and 125 an intermediate opening in the bottom of the wagon, of the hinged door for said opening, and devices, substantially as described, consisting of a shaft supported in the sides of the wagon-body above said opening, said shaft 130 being connected with the door by suitable connections and also connected with other

devices at the driver's seat, whereby he may open and close the door at pleasure while the wagon is in motion, substantially as described.

3. In a wagon for use in road-making, the combination of the wagon-body having the interior inclines sloping from each end toward the middle and the intervening opening in the bottom of the wagon between the ends of the inclines, the hinged door for said opening, the shaft with its pulleys supported in the sides of the wagon-body above the opening, the transverse shaft near the driver's seat, and the connecting-chains running from the door over the first-named pulleys and connected to the shaft near the driver's seat, substantially as described.

4. In a wagon for use in road-making, the combination of the wagon-body having the interior inclines D and E, the opening in the bottom of the wagon between the ends of said inclines, a hinged door F for said opening, the shaft G, the gear H, and the ratchet I on said shaft, the spring-pawl K, engaging the ratchet I, and the chains and rods e d or similar connections between the shaft G and the door F, substantially as described.

5. The combination of the wagon-body with its interior inclines and opening, the door F, the shaft a, carrying pulleys b b, the shaft G near the driver's seat, carrying gear H and ratchet I, the spring-pawl K, engaging ratchet I, the gear L, engaging gear H and provided with crank-handle L, and the chain and rod connections e d between the shaft G and the door F, substantially as described. 30

6. The combination, with the wagon having interior inclines and the bottom opening and the hinged door F, of the shaft a above the opening and provided with the hand-pulleys b b, the shaft G near the driver's seat, the gear H and ratchet I, carried on said shaft, pawl K, engaging the ratchet I, the gear L, engaging gear H and provided with crank-handle L', and the connections fastened to the shaft G, running over the pulleys b b, and connected to the door F, substantially as described. 40 45

In testimony whereof I affix my signature in presence of two witnesses.

GEORGE S. KYLE.
